DESIGN FOR A COMBINED SAUCE BOAT AND BASE THEREFOR

Lurelle Guild, Noroton, Conn., assignor to Kensington, Incorporated, New Kensington, Pa., a corporation of Pennsylvania

Application January 16, 1937, Serial No. 67,097

Term of patent 3½ years

To all whom it may concern:

Be it known that I, Lurelle Guild, a citizen of the United States, residing at Noroton, in the county of Fairfield and State of Connecticut, have invented a new, original, and ornamental Design for a Combined Sauce Boat and Base Therefor, of which the following is a specification, reference being had to the accompanying drawing, forming a part thereof.

Fig. 1 is a top plan view of a combined sauce boat and base therefor embodying my new design.

Fig. 2 is a view in elevation.

Fig. 3 is a partial view in elevation, taken at right angle to Fig. 2, and showing the handle.

Fig. 4 is a cross sectional view taken at right angle to Fig. 2 to show the contour of the base.

I claim:

The ornamental design for a combined sauce boat and base therefor as shown and described.

LURELLE GUILD.
